UNITED STATES PATENT OFFICE.

JAMES P. HENDERSON, OF TOPEKA, KANSAS.

DOOR-JAMB PROTECTOR.

Application filed June 21, 1922. Serial No. 569,789.

To all whom it may concern:

Be it known that JAMES P. HENDERSON, a citizen of the United States of America, residing at Topeka, in the county of Shawnee and State of Kansas, has invented new and useful Improvements in Door-Jamb Protectors, of which the following is a specification.

The object of the invention is to provide a simple and efficient means in the form of an attachment to a door particularly of the screen type as a means of protecting the framework and finish of the door from the contact therewith of the latch hook which usually is loosely or swingingly connected with the door and of which the point or nose has a tendency to mar, scratch or mark the finish of the frame and thereby detract from the appearance thereof; and with this object in view the invention consists in a construction and combination of parts of which a preferred embodiment is shown in the accompanying drawings, wherein:—

Figure 1 is a view of a door provided with a latch or holding hook with a protective attachment embodying the invention applied thereto in the operative position.

Figure 2 is a plan view of the same showing the door and jamb in section.

Figure 3 is a detail view of the protector.

Figures 4 and 5 are detail views of modified forms of the protector.

The protective device in the form illustrated in the drawing is attached to the inner face of the door 10 or that face which carries the fastening or latch hook 11, between the screw eye 12 by which the latch hook is suspended from the door and the free edge of the latter, and consists essentially of a base or fastening plate 13 having an outwardly directed guard flange 14 disposed adjacent to the mounting of the latch hook and provided with an arcuate outer edge to serve as a guide for the shank of the hook in engaging the hook with the catch eye 15 on the door jamb,—said guard flange serving to prevent the latch hook from swinging toward the free edge of the door and catching between the plane of the door and the edge or rabbet of the casing or jamb and serving to deflect the hook end of

the latch toward the hinged edge of the door when disengaged from the catch eye. The guard flange is preferably reinforced terminally by side bracing flanges 16 which in common with the guard flange may be upstruck from the material forming the base or securing plate of the attachment in the construction of a simple and inexpensive article of manufacture as shown separately in Figure 3. The device may be secured to the door by screws 17 or any equivalent fastening means.

The inter-position of the guard flange having the arched guide edge between the pivotal or swinging mounting of the latch hook and the free edge of the door prevents the hook end of the latch from coming in contact with the face of the door jamb and correspondingly prevents the eye at the inner end of the shank from becoming twisted in the screw eye in such a way as to cause the hook end of the latch to project, as above noted, beyond the free edge of the door or into a position which will cause the said hook end to be interposed between the inner surface or face of the door and the rabbet or seat in the door jamb, and consequently prevents that marring of the door jamb and the face of the door which is common particularly in connection with screen doors which are usually spring closed and therefore have a tendency by reason of their lightness and quickness of movement to throw the latch into a position to mar the door or the jamb.

The modified constructions shown in Figures 4 and 5 embody the essential features of the above described form of the device with the addition that there is employed a supplemental attaching plate 13^a designed as a means of strengthening the structure and affording a fender to protect the surface of the door from contact of the hook end of the latch when released or disengaged from the catch eye on the jamb, and in connection with Figure 4 there is employed also a deflector wing 19 which serves to swing the hook inwardly as it drops from its position in engagement with the catch eye, the exposed edge of said wing being obliquely disposed.

Having described the invention, what is claimed as new and useful is:

1. A door jamb protector consisting of a plate having angularly disposed flange portions, and triangular end flanges connecting the first mentioned flange portions together.

2. A door jamb protector consisting of a plate having angularly disposed flange por-

tions, and triangular end flanges connecting the first mentioned flange portions together, the plate having at one end portion a plane portion which is disposed at a right angle to the triangular flanges. 10

In testimony whereof he affixes his signature.

JAMES P. HENDERSON.
